UNITED STATES PATENT OFFICE.

THOMAS SHIPLEY, OF YORK, PENNSYLVANIA.

PURGING SYSTEM FOR REFRIGERATING PLANTS.

Application filed October 19, 1925. Serial No. 63,490.

This invention relates to refrigeration and particularly to devices for purging foreign gases from the system.

These foreign gases are ordinarily air and products resulting from the decomposition of lubricating oils, and have the characteristic of being non-condensable at the pressures and temperatures used in refrigerating systems. This fact renders their presence harmful to the economical operation of the refrigerating system and is availed of for their removal by selective liquefaction.

Various methods involving selective liquefaction have heretofore been proposed. The efficacy of such methods depends on the thoroughness with which the mixture of gases is chilled. It is impossible, according to the law of partial pressures, to produce a complete separation in this way, but a separation complete enough for practical purposes can be had if the mixture of gases is cooled to a sufficiently low temperature and if all parts of the mixture are maintained chilled at the point of purging. This can be done satisfactorily in a device arranged to be manually operated and hence operated only periodically, but it has been found difficult to secure satisfactory results with a device capable of operating automatically and substantially continuously. Continuous automatic operation is obviously desirable.

Generally stated, I withdraw from the system refrigerant in a gaseous state with a rich admixture of foreign gases. This can best be done at points in the system where the refrigerant is normally in a liquid state, for gases and vapors there present will be richest in foreign gases. A convenient way to collect such gas mixture is to interpose a trap in the liquid line as shown in my prior Patents Nos. 1,525,006 and 1,525,007, issued February 3, 1925, or to take advantage of the trapping action inherently present in the conventional type of receiver. This last arrangement is shown in the present application.

The mixture of gases so accumulated is led through one passage of a surface cooler which has another passage through which a cooling medium is passed in counter-flow relation. This cooling medium may conveniently be refrigerant from the system expanded through an expansion valve and returned to the suction side of the compressor, or its equivalent. The effect of the cooler is to liquefy substantially all of the refriger-

erant gas so that the discharge from the cooler consists of liquid refrigerant and non-condensable gases with a very slight admixture of refrigerant in the gaseous state. The discharge from the cooler is received in a drum which preferably encloses the entire cooler and in which a gravity separation of the liquid and gas is effected.

The liquid refrigerant is discharged by automatic means, preferably a float valve, and is returned to the refrigerating system. This may conveniently be done by delivering the liquid refrigerant to the refrigerant passage of the cooler, in which it expands and performs a useful cooling function. The non-condensable gases are discharged through a valve, preferably automatic, the simplest form of which is an ordinary loaded relief valve. This relief valve is set open at a pressure slightly less than receiver pressure in the system so as to induce flow of gases through the cooler.

In order to observe the operation of the device a sight glass is interposed between the refrigerating system and the cooler. This sight glass contains liquid, preferably oil, through which the gases bubble when the system is operating correctly.

Instead of the loaded relief valve above referred to, I may make use of any other suitable type of valve for controlling the purging. A manually operated valve might be used with some success, and there are other types of automatically controlled valve which may be applied and whose use under particular circumstances is contemplated.

The system is illustrated partly in elevation and partly in section in the accompanying drawing.

The receiver is shown at 1. The connection 2 leads from the top of the receiver through a stop valve 3 to the bottom of a sight glass 4. This is substantially filled with a liquid such as oil, through which the gas bubbles upward. From the top of the sight glass 4 connection is made to a two-pipe cooler consisting of an internal pipe 5 and a surrounding cooling pipe 6. These pipes are concentrically arranged and the inner pipe 5, which receives the gases from the sight glass 4, discharges at its lower end 7 into a drum 8 known as the purge drum.

The drum 8 makes a tight joint with the outer pipe 6. On the upper end of the outer pipe 6 is a T coupling 9 to which is con-

neected a pipe 10 leading to the suction side of the compressor or its equivalent forming part of the refrigerating system. A tight joint between the coupling 9 and the pipe 5 is made by means of a thimble 11. The pipe 12 brings liquid refrigerant from some suitable source, such as the receiver 1, and delivers it through an expansion valve 13 to a pipe 14 which extends through the top 10 of the purge drum 8 and connects at 15 with the space between the outer pipe 6 and the inner pipe 5. The pipe 14 makes a tight joint with the purge drum 8 and also with the outer pipe 6 at 15.

Consequently, liquid refrigerant is expanded through the valve 13, passes through the pipe 14 to the annular space between the pipes 5 and 6 of the cooler, thence flows upward through this space, and flows to the 20 compressor through the connection 10. The effect of this is to chill the gases flowing downward through the pipe 5 and also to chill the interior of the drum 8.

It will be observed that the counter-flow principle is availed of in the pipes 5 and 6 so that gases flowing from the receiver 1 are thoroughly chilled, and this chilling action is maintained within the drum 8. Consequently, substantially all the refrigerant 30 flowing down through the pipe 5 is discharged as a liquid at 7 and collects in the bottom of the drum 8. The level of liquid there is indicated by a gauge glass 16 of usual form. The liquid is discharged from 35 time to time through a valve 17 which may be automatically controlled by means of a float 18, though a manually operated valve might be substituted if preferred.

From the valve 17 the refrigerant flows 40 through a pipe 19 to the pipe 14. Hence the valve 17 acts as a sort of expansion valve, admitting liquid refrigerant to the space between the pipes 5 and 6 of the cooler. Since this space is connected with the suction of 45 the compressor, this forms a convenient and efficient way of returning the liquid refrigerant from the bottom of the drum 8 to the refrigerating system.

The pipe 20 leads from the top of the 50 drum 8 and to this is connected a pressure gauge 21 and a loaded relief valve 22 which is set to a pressure slightly less than the pressure in the receiver 1. Accordingly, the relief valve 22 operates to vent from the 55 purge drum 8 the foreign gases which gradually accumulate there. Instead of the pressure controlled relief valve 22 I may substitute other automatic valves, particularly valves subject to the conditions in the drum 60 8. It will be observed that the valve 22 is subject to pressure conditions in the drum and it is desirable that the purge valve be controlled by such conditions, though it is not strictly necessary that this control be 65 by pressure.

Also it is not necessary to adhere strictly to the exact arrangement shown, but a peculiar advantage is had from the use of a counter-flow surface cooler so arranged as to cool not only the flowing gas, but 70 also the interior of the purge drum. Hence I regard the enclosing of the surface cooler within the purge drum as an important feature of the invention.

What is claimed is:—

1. In a purge device for refrigerating systems, the combination of a cooler of the surface type having two passages in heat transferring relation; connections for passing a cooling medium through one passage in said cooler; connections for passing a mixture of condensable refrigerant and non-condensable gas from a refrigerating system through the second passage in said cooler in counter-flow relation to said cooling medium; a 80 chamber for collecting liquid refrigerant condensed in said second passage; and an automatic vent valve subject to conditions in the chamber arranged to discharge uncondensed gases from said chamber. 90

2. In a purge device for refrigerating systems, the combination of a cooler of the surface type having two passages in heat transferring relation; connections for passing a cooling medium through one passage 95 in said cooler; connections for passing a mixture of condensable refrigerant and non-condensable gas from a refrigerating system through the second passage in said cooler in counter-flow relation to said cooling medium; a chamber for collecting liquid refrigerant condensed in said second passage; and a loaded relief valve for discharging uncondensed gases from said chamber. 100

3. In a purge device for refrigerating systems, the combination of a double pipe cooler; connections for passing a cooling medium through one pipe of said cooler; connections for passing a mixture of condensable gaseous refrigerant and non-condensable gas from a refrigerating system through the second pipe of said cooler; a drum enclosing said cooler and arranged to receive the discharge from said second pipe; automatic valve means for withdrawing liquid refrigerant from said drum; and an automatic vent valve arranged to discharge uncondensed gas from said drum. 115

4. In a purge device for refrigerating systems, the combination of a double pipe cooler; connections for expanding refrigerant from a refrigerating system through one pipe of said cooler; connections for passing a mixture of condensable gaseous refrigerant and non-condensable gas from the refrigerating system through the second pipe of said cooler; a drum enclosing said cooler and arranged to receive the discharge from said second pipe; automatic means arranged to withdraw liquid refrigerant 125 130

from said drum and deliver it to the first pipe of said cooler; and an automatic vent valve arranged to discharge uncondensed gas from said drum.

5. In a purge device for refrigerating systems, the combination of a cooler comprising concentric pipes arranged in a substantially vertical coil; connections for expanding refrigerant from a refrigerating system upward through the space between said inner and outer pipes; connections for passing a mixture of condensable gaseous refrigerant and non-condensable gas downward through
- 10

said inner pipe; a drum enclosing said cooler, and arranged to receive the discharge from said inner pipe; a float valve arranged to deliver liquid refrigerant from the bottom of said drum to the space between said inner and outer pipes; and an automatic vent valve subject to conditions within said drum and arranged to discharge uncondensed gases from said drum.

In testimony whereof I have signed my name to this specification.

THOMAS SHIPLEY.
